Primary Examiner — Susan Moon Lee(74) *Attorney, Agent, or Firm* — Duane Morris LLP(57) **CLAIM**

We claim the ornamental design for a portable terminal, as shown and described.

DESCRIPTION

FIG. 1 is a perspective front view of a portable terminal according to the present invention.

FIG. 2 is a front elevation view of the portable terminal of FIG. 1.

FIG. 3 is a rear elevation view of the portable terminal of FIG. 1.

FIG. 4 is a right side elevation view of the portable terminal of FIG. 1.

FIG. 5 is a left side elevation view of the portable terminal of FIG. 1.

FIG. 6 is a top view of the portable terminal of FIG. 1; and, FIG. 7 is a bottom view of the portable terminal of FIG. 1.

Broken lines and unshaded portions contained within broken lines are not claimed.

1 Claim, 7 Drawing Sheets# US D719,574 S
